UNITED STATES PATENT OFFICE.

THOMAS VEITCH, OF BRIELLE, NEW JERSEY.

INDICATOR FOR WATER-COOLED ENGINES.

Application filed September 28, 1923. Serial No. 665,500.

The present invention relates to appliances for use with cooling systems of internal combustion engines, and is more particularly directed toward a device which may be used 5 in connection with the radiator of an ordinary water cooled automobile engine for the purpose of indicating the condition of the cooling water, both as to temperature and quantity, or level.

Internal combustion engines, such as are now in general use in automobiles, differ from other types of power units, in that the power is produced in the cylinders by the 10 explosions, following each other with great rapidity, generate a high degree of heat, so high in fact that, if means were not provided (in addition to proper lubrication) for dissipating a considerable portion of it, the engine 15 parts would be soon destroyed. Cooling means are therefore universally employed for the purpose, the one most generally used being a water system. This consists in surrounding the engine cylinders with a water- 20 jacket connected at the top and bottom to a radiator having a large exposed cooling surface, the arrangement being such that the water is continually passed through the 25 jacket and radiator by means of a pump, 30 gravity, or other suitable means.

While cooling means are necessary, it is nevertheless desirable that the engine be operated at a substantially constant temperature,—and this temperature should be as high 35 as is reasonably safe. Such engines, being heat engines, operate most efficiently at a relatively high temperature; and, if this critical temperature is maintained, a maximum efficiency will result. The design of 40 water cooling systems for engines is based upon the circulation of a predetermined quantity of water in the system so that the water may properly circulate through the cylinder jacket and the cooling section of the 45 radiator. An insufficient supply of water is unable to carry the heat away from the engine, and is unable to fill the cooling section. It is therefore only partly cooled, and engine 50 temperature may rapidly rise to a dangerous degree.

As the operation of the cooling system cannot be directly observed by the driver, and as it is subject to wide temperature variation and to leakage or volatilization of cooling 55 water, it is desirable that suitable instrumentalities be provided so that he can con-

stantly be informed of the condition with a minimum of effort. In automobiles, and the like, a convenient location for an instrument for these purposes is on the radiator cap, and instruments heretofore developed have been designed to indicate one or the other of these conditions in a more or less satisfactory manner.

These temperature indicating instruments 65 consist usually of an ordinary thermometer mounted upon the radiator cap of an automobile, the thermometer having a comparatively short stem, and the bulb, therefore, being normally disposed above the surface of 70 the water in the radiator. As the air space above the water level is always somewhat cooler than the temperature of the water in the radiator, instruments of this character will show a more pronounced rise or reading when the temperature of the cooling system rises from safe to dangerous conditions,—that is, if the water in the top of the radiator is at 200° F., which is a safe operating temperature, the air space in which the bulb of 80 the thermometer is located may be only 180° F. in the summer time and but 150° F. or 160° F. in cold weather. This temperature the thermometer will normally indicate, but, should the temperature of the water rise sufficiently to cause steam to be formed, this 85 steam will fill the air space and affect the thermometer bulb, producing a rapid and corresponding rise in the indication. This construction and method of operation have 90 their advantages, but such instruments are primarily useful for indicating abnormal conditions only. It is however desirable that the driver of a car should at all times know what the water temperature is, and it is 95 applicant's object to provide an instrument that the user can rely upon for obtaining a substantially accurate indication under all operating conditions.

My present invention contemplates an improved form of instrument for the purposes specified, and possesses many advantages not heretofore obtained. The instrument herein described and claimed not only gives an accurate indication of the water temperatures 100 of an automobile engine cooling system, but, in addition, indicates, under all normal conditions, the exact amount or level of the water in the radiator. Not only this, it combines in a single instrument both of these advantageous features, and does so in a simple, 105 compact and most inexpensive way; and it

possesses many advantages and desirable features which will be apparent from the following disclosure.

In the accompanying drawings, there is shown, only for the purpose of illustration, one of the many possible embodiments of the present invention, together with a modified form of indicator element. In these drawings:

10 Fig. 1 is a vertical transverse sectional view taken through the upper tank of an automobile radiator showing the filling spout and instrument attached, parts of the instrument being in section and parts in elevation, the 15 instrument indicating proper cooling water temperature and average water level;

Fig. 2 is a section taken on the line 2—2 of Fig. 1, in the direction of the arrows;

Fig. 3 is a section taken along the line 3—3 20 of Fig. 1 in the direction of the arrows;

Fig. 4 is a developed view showing a form of indicator element;

Fig. 5 is a fragmentary view of the parts shown in Fig. 1, the indicator being in a different position; and

Fig. 6 is a view of the external part of the appliance showing a modification.

An ordinary automobile radiator is illustrated at A in Fig. 1. It has a cooling section 10 of any type, an upper tank 11, adapted to receive the hot water from the engine, and a filling spout or neck 12 threaded at 13 in the customary manner. For proper operating conditions of the automobile engine, this 35 tank should be maintained partly full of water so that the hot water may spread to the entire length of the tank and flow through the cooling section. A suitable water level is indicated in the drawing in the conventional manner.

The indicating instrument is adapted to be mounted upon the ordinary radiator cap 14 which cooperates with the threads 13 of the filling spout 12. The cap 14 is provided with 45 a centrally arranged aperture 15 through which is passed an upright axially disposed tubular member 16. This tubular member may be fastened to the cap member in any convenient manner. It is here shown as provided with threads 17 for a nut 18 which is adapted to be threaded against a washer 19 bearing against the lower surface 20 of the cap 14, the member 16 being provided with a shoulder 21 to abut the upper surface of the 55 cap 14.

The tubular member 16 extends downwardly so that the lower end 22 is adjacent the cooling section 10, and provides a housing and guiding means for the operating mechanism included therein. This tubular member is here shown as being provided with oppositely disposed fins 23 and 24 to act as guides for the movable indicator mechanism. The lower end of the tubular member 22 is 65 perforated as shown at 25 or may be provided

with a fine screen, and a vent 26 which may be screened, if desired, is provided near the cap 14 so that the water level inside the tube will be the same as that in the top tank of the radiator. Making the tubular member substantially closed prevents dirt, scale or other matter from interfering with the operation of the mechanism inside the tube.

A cross member 27, disposed inside the tubular member 16, has bifurcated ends 28 and 29 which ride along the fins 23 and 24. This cross member carries a float 30 which is suitably fastened to it as by means of a hollow rivet 31. The cross member is provided (see Fig. 4) with a laterally extending arm 32 to so which is attached the outer end 33 of a spirally coiled bimetallic thermostatic member 34. The other end 35 of this thermostatic member is attached to the lower end of a slender rod 36 which passes upwardly thru the hollow rivet 31 as shown. This thermostatic member will be submerged in the water, if present, and therefore will be able to accurately operate the indicator mechanism and show water temperature.

The member 16 is provided in some convenient location (here shown as adjacent outside flange 21) with an inwardly directed flange 37. While it is here shown as integral, it may be, if desired, a separate piece. This flange 37 acts to close off the tubular member so as to prevent water vapor from escaping in substantial quantities into the upper part of the member. It is provided with a centrally disposed tubular guide member 38 which surrounds the stem 36. The lower end of this member 38 may conveniently act as a stop, limiting upward movement of the float.

The upper part of the central member 16 is shaped to provide a housing for the movable member. This housing also provides for illuminating the indicator at night and permitting its observation from the driver's seat. As here shown there is a short cylindrical portion 39 above which are disposed two upright spaced apart walls 40 and 41. A glass window or lens 42, plain or frosted, is shown as being fastened between the walls 40 and 41 on the side of the instrument which is intended to be remote from the driver. This will admit light to illuminate an indicator carried therein, especially stray light from headlights at night. The near side 43 of the apparatus is here shown as circular and may be integral with the side walls 40 and 41. The front of the instrument is provided with a centrally arranged vertical slot 44 which is covered with a glass window 45.

The upper end of the stem 36 is provided with an indicator member 46 which is adapted to assume various elevations and various angular positions, depending upon the position of the float and temperature of the thermostat which, in the present construction, is

the same as that of the cooling water. As here shown, this indicator element is capable of showing various conditions of temperature. When the cooling water is at proper operating temperature, (say 180° F.) the central diamond shaped element 47 may be disposed in line with the slot 44. Whenever the water temperature is below the best operating temperature, the thermal element will have brought the element 48 in line with the slot 44. This element 48 may be painted a green color if desired. When the temperature is so high as to be dangerous, the thermal element will have brought the disc 49 in line with the slot 44 (see Fig. 5). The level of the water in the tank A will be indicated by the position of the indicator element 46 along the slot 44. This is brought about by the rising and falling of the indicator mechanism, as the float 38 follows the water level. As long as there is sufficient water in the upper tank, the device is preferably so arranged that the indicator element remains within the range of the slot 44. If, however, the water level becomes too low, or the water disappears from the upper tank, then the float lowers the indicator mechanism until the float reaches the bottom of the tubular member 16. By this time the indicator elements have been withdrawn from view and hidden in the cylindrical portion 39. The device cannot then give an observable temperature indication.

Fig. 6 shows a modification. The lower end of the device may be made in any suitable manner such as has heretofore been described in detail. Instead of the single centrally located slit, this indicator is provided with two slits 50 and 51 separated by the narrow strip 52. An indicator element 53 is carried on the upper end of the stem 36 as before described. This indicator element, however, is in the form of an arcuate or cylindrical strip, preferably metal, which is provided with suitable calibrations 54 whereby the temperature of the water may be read.

The device is preferably constructed in such a way that the movable parts are carried sufficiently loose to permit them to be actuated by a comparatively light weight float and a comparatively small thermostat. In this way the inertia of the moving system is reduced, and the likelihood of injury as by jamming of the parts is diminished. It will be noted that the movement of the float member is limited by the abutment against the closed end 22 of the tube 16 or against the end of the tube 38. In this way any tendency to bend or buckle the thin shaft 36 is avoided.

From the foregoing, it will be appreciated that the device above described will afford a convenient indication of the temperature of the water so that the driver may observe the temperature at all times, while there is sufficient water for proper operation of the

motor. The operator gets an accurate reading of water temperature, which accurately indicates the operating condition of the engine, instead of receiving an indication of the air conditions above the water which is not a reliable indication of the conditions in the engine. The operator is also able to observe and determine at all times the water level in the radiator at the same time that he is observing its temperature. 75

In the instrument as shown in Figures 1 to 5 a visual indication is given of water temperature conditions, that is, the indicator, having the diamond and circular shaped members which are brought into view in the operation of the thermostatic element, simply indicate normal or abnormal temperature conditions. In the form shown in Fig. 6, however, the indicator member is of such form as to enable the driver to observe at 80 all times the temperature of the water in the radiator tank in degrees Fahrenheit. These instruments simultaneously indicate the temperature of the water and its level and are so designed that it is impossible for them to 85 give a false indication of either water temperature or water level. The withdrawal of the indicator element into the space below the windows hides it and effectively warns the operator of the improper functioning of the 90 cooling system. It gives a definite warning of an unsafe condition. 95

A form of indicator such as that disclosed in Figs. 1 to 5 wherein the observable parts are of different shapes or characters, is advantageous in that it can be readily seen at 100 night, either by suitable side lights on a car, or against the reflected light from the searchlights. The particular shapes shown are for illustrative purposes only, and are not 105 to be taken in any way as restrictive.

It is obvious that my invention may be embodied in many forms and constructions, and I wish it specifically understood that the particular forms shown and described are but 110 two of many forms. Various modifications and changes being possible, and possibly advantageous, I do not limit myself in any way with respect thereto.

What I claim as new and desire to secure by 115 Letters Patent, is:

1. An indicator device for the cooling system of an internal combustion engine, comprising an element responsive to the temperature and to the level of the cooling water, said element comprising a vertical reciprocating level indicator and a rotating temperature indicator, both of which are simultaneously operable. 120

2. An indicating device for the cooling system of an internal combustion engine including, in combination, a shaft adapted for reciprocal and rotary movement, an indicating element carried by said shaft at the upper end thereof, a float and a thermally responsive 125

- device supported by and carried underneath said float, said shaft being carried and actuated by said thermally responsive device, and said thermally responsive device being movable with the shaft. 5
3. An indicator device for the cooling system of an internal combustion engine, comprising a shaft adapted for reciprocal and rotary movement and carrying an indicating element at its upper end, a float, a thermally responsive device supported by and carried underneath the float, the shaft being carried by the thermally responsive device, and stops limiting the movement of the float. 10
- 15 4. An indicator device for the cooling system of an internal combustion engine, comprising a float, a vertical shaft, and a thermostat carried by the float, the shaft being carried and actuated by the thermostat and an indicator operable by said shaft. 20
- 25 5. An indicator device for the cooling system of an internal combustion engine, comprising a float reciprocating vertically in response to the level of the cooling water, a vertical shaft, and a thermostat carried underneath the float, the shaft being supported by the thermostat and revolvable by the same in response to change in temperature and an indicator operable by said shaft. 30
- 35 6. An indicator device for the cooling system of an internal combustion engine, comprising a frame, a float mounted for reciprocation, and a vertical shaft having a connection with the float to be moved vertically thereby, said connection including a thermostat effective to rotate the shaft upon change of temperature and an indicator operable by said shaft. 40
- 45 7. An indicator device for the cooling system of an internal combustion engine, comprising a radiator cap having a hollow exposed upper portion, an indicator element therein, and means to move the indicator element up or down in response to change in level of the cooling water, means to rotate the indicator element in response to cooling water temperature, a housing having a slit extending nearly to the bottom thereof, the space below the slit being sufficient to hide the indicator when the water level is below a predetermined level so that temperature in the air space is not indicated. 50
- 55 8. An indicator device for the cooling system of an internal combustion engine having a single gauge for indicating both temperature and cooling water level, and means including a member for lowering the device from view when the water level is below a predetermined level. 60
- 65 9. An indicator device for the cooling system of an internal combustion engine having means comprising an indicator for designating both temperature and cooling water level, said means including a thermo-responsive element normally positioned in the cooling water but adapted to be positioned in the air space above the water when the latter falls below a predetermined level, and means including a float to render the device ineffective for indicating the temperature of the air space above the water by lowering the device from view when the water is below said predetermined level. 70
- 75 10. An indicator device for the cooling system of an internal combustion engine, comprising a vertical tubular member, an indicating element mounted therein for longitudinal and angular movement, means to move the element longitudinally in response to liquid level, and means to move it angularly in response to liquid temperature. 80
- 85 11. An indicator device for the cooling system of an internal combustion engine, comprising a vertical tubular member, an indicating element mounted therein for longitudinal and angular movement, means to move the element longitudinally in response to liquid level, means to move it angularly in response to liquid temperature, and means to permit observation of the indicator element during only a part of its longitudinal movement. 90
- 90 12. In an indicating device for the cooling system of internal combustion engines, a radiator cap, a member disposed axially of said cap and having a tubular lower end, a float, a thermostat carried by the float, means for guiding the float for reciprocation inside said lower end, a shaft carried by the thermostat and extending above the radiator cap, and fixed stops for the float. 95
- 100 13. In an indicating device for the cooling system of internal combustion engines, a radiator cap, a member disposed axially of said cap and having a tubular lower end, a float, means for guiding the float for reciprocation inside said lower end but restraining rotation thereof, a shaft mounted for relative rotation on the float and extending above the radiator cap, and fixed stops for the float, one of said stops being in the form of a narrow guiding tube for the shaft. 105
- 110 14. In an indicating device for the cooling system of internal combustion engines, a radiator cap, a member disposed axially of said cap and having a tubular lower end, a float, a thermostat carried by the float, means for guiding the float for reciprocation inside said lower end, a shaft carried by the thermostat and extending above the radiator cap, and fixed stops for the float, one of said stops being in the form of a narrow guiding tube permitting reciprocation and rotation of the shaft. 115
- 120 15. In an indicating device for the cooling system of internal combustion engines, a radiator cap, a member disposed axially of said cap and having tubular lower end, a float, a cross member carried by the float and having bifurcated ends, guides embraced by the bifurcations and carried inside said lower end, a thermostat carried underneath the float and 125
- 130

a shaft extending above the radiator cap, said shaft being connected to the thermostat to be rotated thereby and to be bodily moved by the float.

- 5 16. An indicating device for the cooling system of an internal combustion engine, comprising a frame adapted to be exposed above a radiator filling cap, a front window, a spaced rear window through which exterior 10 light may pass to the front window, and a reciprocable and revolvable indicating member interposed between the windows, said member serving to indicate both temperature and cooling water level.
- 15 17. An indicating device for the cooling system of an internal combustion engine, comprising a frame adapted to be exposed above a radiator filling cap, a front window, a spaced rear window through which exterior light 20 may pass to the front window, a reciprocable and revolvable indicating member interposed between the windows, and means to reciprocate the indicator in response to water level, said indicator revolving responsive to temperature changes in the liquid.

- 25 18. An indicating device for the cooling system of an internal combustion engine including, in combination, a frame adapted to be exposed above the radiator filling cap, spaced 30 front and rear windows carried by said frame, an indicating member positioned between said windows, supporting means for mounting said indicating member for rotary and for translatory movements, temperature-responsive means for operating said indicating member in one of its movements to effect temperature indication, and means responsive to water level for operating said indicating member in another of its movements to effect water 35 level indication.

- 40 19. An indicating device for the cooling system of an internal combustion engine, comprising a frame adapted to be exposed above a radiator filling cap, a front window, a spaced rear window, a reciprocable and revolvable indicating member interposed between the windows, means to reciprocate the indicator in response to water level, and means to rotate the indicator in response to 45 water temperature.

- 50 20. An indicating device for the cooling system of an internal combustion engine, comprising a frame adapted to be exposed above a radiator filling cap, a front window, a spaced rear window, an indicating member inter-

posed between the windows, a mount supporting said indicating member for translatory and rotary indicating movements and a well or chamber below the windows in which the indicating member may be hidden from view. 60

21. An indicating device for the cooling system of an internal combustion engine, comprising a frame adapted to be exposed above a radiator filling cap, a front window, a spaced rear window, a reciprocable and revolvable 65 indicating member interposed between the windows, means to reciprocate the indicator in response to water level, means responsive to temperature changes to revolve said indicating member, and a well or chamber below 70 the windows in which the indicating member may be hidden from view when the water level is below a predetermined level.

22. In an indicator device for the cooling system of an internal combustion engine, the combination with a radiator cap, of a member disposed axially thereof and having a tubular lower end, a float, a cross member carried by the float and having bifurcated ends, guides carried inside the said lower end, a thermostat 75 carried underneath the float, said float being vertically reciprocable, a shaft connected to said thermostat and extending through said radiator cap, an indicator device at the upper extremity of said shaft, said shaft being rotated by the thermostat, and reciprocated by the movement of the float.

23. In an indicator device for the cooling system of an internal combustion engine, the combination with a vertically reciprocable 90 float member, of stops for limiting the movement thereof in a vertical plane, guide members for preventing the angular movement of said float member, a thermostat carried underneath said float member, a shaft attachable to and rotatable by said thermostat, and indicating means at the upper extremity of said shaft, said indicating means being actuated vertically by said float and angularly by said thermostat.

24. An indicating device for cooling systems of internal combustion engines including, in combination, an indicator, means for supporting said indicator for a plurality of independent movements, temperature-responsive means for effecting one movement of said indicator, and means responsive to water level for effecting another movement of said indicator. 105

THOMAS VEITCH.
